UNITED STATES PATENT OFFICE.

WILLIAM MARTIN O'KEEFE, OF BIRMINGHAM, ENGLAND.

FOUNDRY MOLDING-MACHINE.

1,347,119.

Specification of Letters Patent. Patented July 20, 1920.

Application filed August 11, 1919. Serial No. 316,848.

To all whom it may concern:

Be it known that I, WILLIAM MARTIN O'KEEFE, a subject of the King of Great Britain and Ireland, residing at Sydney 5 Works, Stanhope street, in the city of Birmingham, England, have invented certain new and useful Improvements Relating to Foundry Molding-Machines, of which the following is a specification.

10 This invention relates to foundry molding machines, and has for its object to construct an improved machine of simple design whereby the consolidation of the sand around the pattern can be conveniently 15 effected.

The invention comprises the use beneath the pattern and molding box, of a pair of levers so arranged that by means acting on the adjacent ends of the levers the opposite 20 ends can be caused to lift the pattern and box, the levers being subsequently released and the free fall of the pattern and box utilized to consolidate the sand placed in 25 the box. Also the invention comprises the combination and arrangement with the foregoing of means for turning over the box and for supporting the same in the inverted position.

In the three accompanying sheets of explanatory drawings:—

Figure 1 is a side elevation of a molding machine constructed in accordance with this invention.

Fig. 2 is a front elevation with part in section of the upper portion of the machine showing the lever mechanism used in the molding operation and Fig. 3 is a plan of the same with the top plate removed.

Fig. 4 is a part sectional elevation of the 40 table for supporting the inverted box.

In carrying the invention into effect as shown, a pair of forked levers *a* are pivoted on shafts *c* in an approximately horizontal position in the body *b* of the machine. 45 The outer forked ends of the levers *a* are arranged to act upon the underside of a plate *d* which rests upon the upper side of the body. This plate may serve to carry a separate pattern plate. When as in the 50 machine shown it is desired to make provision for turning over the molding box another plate *l* is arranged to rest on the plate *d*. In this case the molding box *e* is carried on the plate *l*. Adjacent to the 55 levers is mounted a rotatable shaft *f* having secured to it a wedge-like cam *g* which

when rotated can pass between the adjacent ends of the levers and by depressing the latter causes the outer ends of the levers to lift the plates *d* and *l* and the superimposed 60 molding box which is filled with sand. When the cam leaves the levers the plates and box are released and are returned to the original position by their free fall. The impact of the plates and box on the 65 upper side of the machine body causes the loose sand to consolidate, the operation being repeated until the required solidity of the mold is obtained.

To minimize friction between the cam and 70 levers swiveling rollers *h* are provided on the levers for engagement by the cam. Also rollers as *i* may be arranged on the ends of the levers which lift the plate. It will be seen in the drawings that the outer ends of 75 each lever are spread apart so that they act on the pattern plate near its four corners and lift the plate evenly. The rollers *h* are arranged to yield against springs *j* in order to minimize shock on the driving 80 gear when the cam first comes into contact with the roller. An oil bath may be provided beneath the cam for lubrication of the cam.

Actuation of the cam may be effected by 85 hand power from a wheel *k* through a chain and sprocket mechanism as shown, or by mechanical power. To prevent displacement of the plate *d* relatively to the machine frame when lifted by the levers, guide pins 90 engaging holes in the body may be provided on the plate, or the plate may be formed with a deep flange *m* around its edges as shown. Also any ordinary provision is made for securing the molding box to prevent displacement relatively to the plate *l* either during molding or in the subsequent 95 operation of turning over. To enable the molding box to be turned over a pair of arms *n* are adapted to be detachably connected to the plate *l*. These arms are secured to a shaft *o* carried on brackets *o'* and movable by a lever *p*. At the rear of the machine is an adjustable rising and falling table *q* on to which the box can be placed in 100 the inverted position by means of the arms *n*. Referring to Fig. 4 the table *q* is formed with a stem *r* adjustable within a plunger *s*. The table can be adjusted vertically in relation to the plunger and locked by a clamping 105 device consisting of a friction block *t* actuated by a screw *u*. The plunger which

can slide vertically in a cylinder v is counterbalanced by weights w acting on chains or cables w passing over pulleys x on the cylinder and attached to extensions y on the plunger. Movement of the plunger is controlled by a lever z pivoted on the cylinder. On one side of its fulcrum this is formed with a wedge cam 2, and on its opposite side with a brake block 3. When the lever is released a spring 4 acting on an arm 5 of the lever forces the wedge cam against the plunger and causes the latter to be held. Downward pressure on the lever releases the wedge cam and presses the brake into contact with the plunger. Normally the table is so counterweighted that on releasing the plunger it can be raised by a relatively small lifting effort into the position for receiving the molding box. In Fig. 1 the plunger is shown in its lower position. With the molding box charged with sand resting on the table, release of the wedge cam permits the plunger to descend, this movement being controlled by the brake.

It will be understood that the arms n are not connected to the table during the molding operation, but are disconnected therefrom. After the box has been deposited in the inverted position on the table q it is disconnected from the plate l and lowered by operation of the table. The plate l can then be returned to the original position.

A machine as above described is simple and effective and well adapted for foundry use. Variations of detail may be introduced to meet different requirements.

Having thus described my invention what I claim as new and desire to secure by Letters Patent is:—

1. In foundry molding machines, the combination with a body, a movable plate supported on the body and arranged to carry a molding box and pattern, levers pivoted on the body with ends adjacent and the outer ends located beneath the plate, and a rotary wedge like cam adapted during a part of its rotation to act on the adjacent ends of the levers for raising the outer ends with the plate, the levers and plate being permitted to return by free falling of the plate when released by the cam, substantially as described.

2. In foundry molding machines, the combination comprising a body, a quadrilateral plate supported on the body and arranged

to carry a molding box and pattern, forked levers pivoted on the body and having their double ends located beneath and near the corners of the plate, their single ends being situated adjacently, rollers and springs on the single adjacent ends of the levers, a wedge like rotary cam adapted to act upon the rollers during a part of each revolution, a shaft carrying the cam, and means for rotating the shaft, the table being raised by the action of the cam on the levers and permitted to fall freely when the levers are released by the cam, substantially as described.

3. In foundry molding machines, the combination comprising a body, a plate supported on the body, and arranged to carry a molding box and pattern, a pair of levers having one pair of ends adjacent and the opposite outer ends located beneath the plate, a cam arranged to act on the adjacent ends of the levers for raising the plate, the latter being permitted to fall freely when the levers are released by the cam, arms pivoted on the body and adapted to be detachably connected with the molding box, and a supporting table on to which the box can be transferred and supported, the box being inverted during transfer, substantially as described.

4. In foundry molding machines, the combination comprising a body, a plate supported on the body and arranged to carry a molding box and pattern, levers pivoted on the body, a cam acting on the levers for raising the plate, the latter being permitted to fall freely when the levers are released by the cam, arms pivoted on the body and adapted to be detachably connected to the box, a supporting table to which the box can be transferred by the arms, a plunger on which the table is adjustably mounted, counterweights for the plunger, a cylinder in which the plunger can slide, means for clamping the table to the plunger, a wedge cam for securing the plunger to the cylinder, a brake for controlling the movement of the plunger, relatively to the cylinder, a lever by which the wedge cam and brake can be actuated, and a spring acting on the lever for automatically bringing the wedge cam into action, substantially as described.

In testimony whereof I have signed my name to this specification.

WILLIAM MARTIN O'KEEFE.
